UNITED STATES PATENT OFFICE.

JOHN HENRY WILLIAMS, OF TEXARKANA, ARKANSAS, ASSIGNOR OF ONE-HALF TO T. W. PALMER, OF GONZALES, TEXAS.

LOCOMOTIVE-BRAKE.

SPECIFICATION forming part of Letters Patent No. 314,209, dated March 17, 1885.

Application filed October 28, 1884. (No model.)

To all whom it may concern:

Be it known that I, JOHN HENRY WILLIAMS, a citizen of the United States, residing at Texarkana, in the county of Miller and State of Arkansas, have invented certain new and useful Improvements in Steam and Air Brakes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention has relation to steam and air brakes; and it consists in the novel construction and arrangement of its parts.

In the accompanying drawings, Figure 1 is a side elevation of a locomotive-engine with 20 some of its parts removed, showing my brake attached. Fig. 2 is a detail view.

My invention is described as follows: The 25 brake-shoes *a a* are supported by rods *b b*, the upper ends of which are pivoted to the side rail, *f*, of the engine-frame, while the lower ends are pivoted to the brake-shoes. The 30 tightening-rod *c c* are pivoted to said brake-shoes at one end, while the other end is pivoted to the lower end of the lifting-rod *e*. On the side rail, *f*, of the engine-frame is 35 erected a fulcrum, *g*. On this fulcrum is pivoted a lever, *h*. To the short arm of this lever *h* is pivoted the lifting-rod *e*. To the long arm of this lever *h* is pivoted the piston-rod *i*, bearing a knuckle-joint, *i'*. This piston-rod works 40 through the guide *j* of the steam or air cylinder *k*. The cylinder *k* is attached to the side of the cab, and steam is conducted to the same by pipes leading from the steam-chest, and is 45 operated by levers and throttle-valves in the usual way; but it may be attached to the engine in front of the driving-wheels, in which case it will be operated in the same manner as when attached to the side of the cab. The 50 lever *h* has a flange or blade, *h'*, running along its lower side its entire length. This blade is to give great strength to it under perpendicular pressure, and allows of its being sufficiently strong without being too large. The steam or air enters at the upper end of the cylinder

k and presses the long end of the lever *h* downward. This draws the lifting-rod *e* upward and throws the brake-shoes *a a* against the driving-wheels.

In order to give the lever *h* a quick and certain upward motion when the pressure of the steam or air is taken off the piston and quickly withdraw the brake-shoes *a a* from contact with the driving-wheels and hold them from such contact until the pressure is again applied, I use an S-spring, *l*, the lower end of which is bolted to the upper face of the rail *f*, and the upper end is bolted to the lower face of the lever *h*, at the extremity of its long arm.

The knuckle-joint *i'* is used in the piston-rod *i*, so that the upper end of the said rod above the said joint may move perpendicularly up and down in the guide *j*, while the part below the said knuckle-joint will accommodate itself to the slight circular motion caused by the up-and-down motion of the lever *h*.

Having thus described my invention, what I claim as new, and desire to secure by Letters Patent, is—

1. In a locomotive-engine having brake-shoes *a a*, rods *b b*, and tightening-rod *c c*, the combination therewith of lifting-rod *e*, its lower end pivoted to the inner ends of the tightening-rod *c c*, and its upper end pivoted to the short arm of lever *h*, with lever *h* pivoted on fulcrum *g*, piston-rod *i*, pivoted to the long arm of said lever, said rod *i* having knuckle-joint *i'*, the upper part of said rod working up and down through the guide *j*, and attached to the piston, steam or air cylinder *k*, having the guide *j*, and S-spring *l*, bolted to the upper face of rail *f* and the lower side of lever *h*, substantially as shown and described, and for the purposes set forth.

2. In a locomotive steam or air brake having shoes *a a*, rods *b b c c*, and lifting-rod *e*, lever *h*, having flange or blade *h'*, having its short arm pivoted in the upper end of lifting-rod *e*, with fulcrum *g*, mounted on the upper face of the rail *f* and bearing the said lever *h* in its upper end, piston-rod *i*, pivoted to the long arm of the said lever *h* and working through the lower head of a cylinder, *k*, substantially as shown and described, and for the purposes set forth.

3. In a locomotive steam or air brake operated by means of a lever, *h*, the combination of the piston-rod *i*, having the knuckle-joint *i'*, with the guide *j*, attached to the lower head 5 of cylinder *k*, substantially as shown, and for the purposes set forth.

4. In a locomotive steam or air brake operated by means of a lever, *h*, the combination of the cylinder *k*, piston-rod *i*, having knuckle- 10 joint *i'*, by means of which the end of said lever is thrown down, with S-spring *l*, the lower

end bolted to upper face of rail *f*, and its upper end bolted to the lower side of lever *h*, by means of which the end of said lever is thrown up, substantially as shown, and for the purposes set forth. 15

In testimony whereof I affix my signature in presence of two witnesses.

JOHN HENRY WILLIAMS.
